UNITED STATES PATENT OFFICE.

HARRY L. ALLEN, OF ALLIANCE, OHIO, ASSIGNOR TO AMERICAN STEEL FOUNDRIES, OF NEW YORK, N. Y., A CORPORATION OF NEW JERSEY.

SAND-RECLAIMER.

1,124,830.

Specification of Letters Patent.

Patented Jan. 12, 1915.

Application filed March 14, 1912. Serial No. 683,757.

To all whom it may concern:

Be it known that I, HARRY L. ALLEN, a citizen of the United States, and resident of Alliance, in the county of Stark and State 5 of Ohio, have invented certain new and useful Improvements in Sand-Reclaimers, of which the following is a specification.

My invention relates to the art of metal founding and has particular reference to a 10 device for reclaiming sand after being used in the production of castings in sand molds.

It is well known that in the formation of molds in which metal castings are made, sand is used to a large extent and this sand 15 to be suitable must have particular characteristics, that is, a certain proportion must be sharp and to this end dust must be eliminated therefrom. It has been customary to entirely discard the sand after being once 20 used, and inasmuch as such sand was easily procured the cost was slight; furthermore to separate the sharp sand from the dust entailed some expense. However, in large 25 establishments where extensive founding is carried on the item of sand becomes considerable and for this reason many forms of apparatus have been devised whereby the sand after being once used may be treated, to the end that the dust and fine particles 30 may be removed and the sharp sand returned to the foundry for reuse. However, the original cost as well as the cost of operation of many of these reclaiming devices has made such processes so expensive that it 35 was equally economical to procure new sand. Inasmuch as the density or volume of the falling sand is greatest immediately below the baffles, it is proposed to apply the greatest amount of suction to the falling stream 40 of sand immediately beneath the baffles, because it will require a stronger suction or current of air to separate the lighter particles than will be required to effect the 45 separation in the lower portions of the falling stream of sand where the particles of sand have become more widely separated, and it is for this purpose that the perforations 17 are provided in greater numbers immediately below the baffles 18.

50 It is the principal object of my invention therefore to provide apparatus which shall efficiently act upon used sand whereby the fine particles may be removed leaving the sharp sand for reuse. It is a further object 55 to produce such a machine which shall be

simple and inexpensive in construction and economical in operation.

The principle of the present machine is that of allowing the sand to pass over a series of baffles whereby the particles are 60 separated and each thereof exposed to a blast of air, the lighter particles being held in the air in suspension, the heavier particles falling by gravity into a proper receptacle.

65 It will be seen therefore from a consideration of my invention that I have provided sand reclaiming apparatus having no moving parts and requiring practically no motive power.

70 My invention will be more readily understood by reference to the accompanying drawings, wherein,

75 Figure 1 is a central, vertical section of a device constructed in accordance with my invention; Fig. 2 is a section on the irregular line 2—2 of Fig. 1, and Fig. 3 is a front elevation.

80 Referring more particularly to the drawings it will be seen that my reclaiming device employs the principle of gravity; the only power required is that necessary to produce the air blast for proper separation.

85 The casing is formed with double walls, an outer wall 10 and inner wall 11. At the top the space between the two walls is closed by a plate 12, the entire top being covered by a screen 13. The outer wall is provided with an exhaust outlet 14, and is 90 perforated to provide sleeves or conduits 15, whereby air may be admitted to the interior of the separator. At the bottom at one side, both walls are terminated to provide a cleaned sand outlet 16.

95 The inner wall 11 is provided with a large number of perforations 17, and with inclined baffles or deflectors 18. These deflectors are also perforated at 19, as will be later described. It will be noted that the perforations 17 in the side walls are located 100 more closely together just beneath the deflectors 18. The lowermost deflector 20 is imperforate and acts merely as a chute to direct cleaned sand to the opening 16.

105 A platform 21 is provided on which sand to be cleaned is placed and a workman standing on the platform shovels sand onto the screen 13. An exhaust fan, not shown, being connected with the outlet 14, it will be seen that a blast of air is drawn in 110

2

through the conduits 15, to the interior of the casing. This air escapes through the openings 17 in the inner wall into the space between the two walls, thence out the opening 14. The sand after passing through the screen 13, falls on the first deflector and is broken up, part thereof passing through the openings 19, some falling over the ends onto the deflector therebelow, where the operation is repeated. As the sand passes down through the separator it will be seen that each particle is subjected to a blast of air and if found to be of a weight insufficient to withstand the blast of air, it will be picked up and carried out through the openings 17 and the exhaust outlet 14, into a dust collector, not shown, the cleaned sand or heavier particles being of a weight sufficient to prevent their being held in suspension or carried by the blast of air, will drop through the device onto the deflector 20 and out the opening 16.

The inclination of the deflectors, the size and disposition of the openings and other details of the construction may be modified, all without departing from the spirit of my invention.

I claim:

1. In a sand reclaimer, the combination of a pair of casings one within the other in spaced relation, perforated deflectors within said inner casing, said casing being provided with a plurality of openings at points beneath each of said deflectors, said openings providing communication with the spaces between said casings, means for partially exhausting the air within said casings and thereby removing dust from the sand, and means for admitting atmospheric air to said inner casing, substantially as described.

2. In a device of the class described, the combination of a casing, a second casing

within said first mentioned casing, the walls of said casings being spaced apart, deflectors having perforations mounted within said second casing, said deflectors being oppositely disposed and inclined downwardly, said inner casing being provided with a series of perforations at its sides, the larger number of perforations being located just beneath the inclined deflectors, and means for passing a blast of air around said deflectors and between the walls of said casings, substantially as described.

3. In a device of the character described, the combination of inner and outer spaced casings, the space between the casings being closed to the atmosphere, the inner casing having an inlet at its top for the introduction of the material to be treated, there being perforations in side walls of the inner casing, baffles in the inner casing, a suction conduit communicating with the space between the casings, and conduits connecting the interior of the inner casing with the atmosphere.

4. In a device of the character described, the combination of inner and outer spaced casings, the space between the casings being closed to the atmosphere, the inner casing having an inlet at its top for the introduction of the material to be treated, one pair of opposite sides of the inner casing having perforations therein, air conduits piercing other sides of the inner casing and communicating between the atmosphere and the interior of said casing, baffles in the inner casing, and a suction conduit communicating with the space between the casings.

HARRY L. ALLEN.
